ABSTRACT

The ignition system is provided at least two coils for generating voltages with phase different from each other. One of the coils charges a capacitor and the other mainly generates an electric signal for preventing reverse rotation. During the reverse rotation of the engine, said other coil so operates as to let the capacitor charging current flow not to the capacitor but to the ground, thereby preventing ignition sparks.

**CAPACITOR DISCHARGE TYPE CONTACTLESS
IGNITION SYSTEM FOR INTERNAL
COMBUSTION ENGINES**

BACKGROUND OF THE INVENTION

1. Field of the Invention

The present invention relates in general to a capacitor discharge type ignition system for internal combustion engines in which a magneto generator is employed as an electric power source for charging a capacitor, and especially to the system for preventing the engines from rotating in the reverse direction.

2. Description of Prior Art

In a conventional ignition system of this kind, a single magnetic pole is formed at a spherical portion of a rotor. Since the generator has a small space to provide a magnet it can not produce a sufficient energy to produce ignition sparks at spark plugs. And further when the magneto generator is provided with a lamp load generating coil, it can not produce a sufficient energy on the lamp load coil, either.

SUMMARY OF THE INVENTION

It is, therefore, a primary object of the present invention to provide a capacitor discharge type ignition system employing the conventional magneto generator which has a plurality of magnets spaced apart at equal intervals.

It is another object of the present invention to provide the ignition systems which prevent the engine from rotating in a reverse direction.

It is a further object of the present invention to provide the ignition system in which the capacitor is prevented from being charged during the reverse rotation of the engine, thereby to prevent the engine from rotating in the reverse direction.

It is a still further object of the present invention to provide the ignition system employing the magneto generator having a plurality of magnets spaced apart at equal intervals, in which at least two generating coils are provided on the stator for charging the capacitor, each phase of the generating voltages of which is different from each other to be detected to prevent the engine from rotating in the reverse direction.

It is a still further object of the present invention to provide the ignition system in which a transformer is connected to the generating coil for producing an ignition timing signal, thereby eliminating the timing signal generator.

It is a still further object of the present invention to provide the ignition system in which another thyristor besides the thyristor for ignition sparks is provided between both terminals of the generating coil for invalidating the generating voltages of the generating coil during the reverse rotation of the engine.

The novel features which are considered as characteristic for the invention are set forth in particular in the appended claims. The invention itself, however, both as to its construction and its method of operation together with additional objects and advantages thereof, will be best understood from the following description of specific embodiments when read in connection with the accompanying drawings.

BRIEF DESCRIPTION OF THE DRAWINGS

FIGS. 1, 4, 5, 7, 8, 10, 11, 13, 17, 19, 21 and 24 are respectively electric wiring diagrams of first to twelfth embodiments of the present invention;

FIG. 2 shows a partially transverse sectional view of an internal rotor type magneto generator employed in the first embodiments of the present invention;

FIGS. 3, 6, 9, 12 and 20 are waveform diagrams for explaining the operation of the embodiments;

FIG. 14 is transverse sectional view of an external revolving type magneto generator employed in the seventh and eighth embodiments of the present invention;

FIG. 15 shows another external revolving type magneto generator, in which FIG. 15-A is a perspective view of the stator of the magneto generator and FIG. 15-B is a rough plan view thereof;

FIG. 16 shows an external revolving type magneto generator employed in the third and fourth embodiments of the present invention, in which FIG. 16-A is a plan view of the stator of the magneto generator and FIG. 16-B is an elevational view thereof;

FIG. 18 shows an external revolving type magneto generator employed in the ninth embodiment of the present invention, in which FIG. 18-A is a longitudinal sectional view taken along the line XVIIIA—XVIIIA in FIG. 18-B and FIG. 18-B is a transverse sectional view taken along the line XVIIIB—XVIIIB in FIG. 18-A;

FIG. 22 shows another external revolving type magneto generator employed in the ninth embodiment of the present invention, in which FIG. 22-A is transverse sectional view taken along the line XXIIA—XXIIA in FIG. 22-B and FIG. 22-B is a longitudinal sectional view taken along the line XXIIB—XXIIB in FIG. 22-A;

FIG. 23 is waveform diagram of the ninth embodiment employing the magneto generator shown in FIG. 22; and

FIG. 25 shows an ignition cycle of the twelfth embodiment shown in FIG. 24.

**DESCRIPTION OF THE PREFERRED
EMBODIMENTS**

Now referring to FIG. 1 showing the first embodiment of the present invention, numerals 1 and 2 designate first and second capacitor charging coils. Said first coil 1 which is mainly used at low speed rotation has a larger number of turns than that of said second coil 2 which is mainly used at high speed rotation. Numerals 3 and 4 designate battery charging coils, and 5a, 5b and 5c generating coils for other electric loads. A numeral 6 designates a pole core wound with said first coil 1, 7 a pole core for said second coil 2 and said battery charging coil 3. Numerals 8, 9 and 10 designate pole cores for said generating coil 5a, 5b and 5c, respectively and 11 a pole core for said battery charging coil 4. Those elements mentioned above constitute as a whole a magneto generator G. Said first coil 1 has a center tap 1c and comprises two winding parts 1a and 1b. A numeral 12 designates a diode, 13 a capacitor, 14 a diode, 15 and ignition coil having a primary winding 15a and a secondary winding 15b, 16 spark plugs mounted on each cylinder of a two-cylinder-two-cycle engine, 17 a thyristor constituting a semiconductor switching element, 18 and 19 diodes, 20 a transformer having a primary winding 20a and a secondary winding 20b for controlling said thyristor 17, 21, 22, 23 and 24 diodes respectively, 25 a battery installed in a vehicle,

26 a full-wave rectifier, 27a and 27b switch means for connecting an output terminal of said rectifier and lamp loads 28.

The construction of the above-mentioned magneto generator of a four-pole type will be described with references in FIG. 2, in which a numeral 29 designates a stator comprising six pole cores 6, 7, 8, 9, 10 and 11 extending internally at equal intervals, and coils 1 to 5c are wound thereon as previously mentioned. A numeral 30 designates a rotor comprising a permanent magnet 32 circumferentially polarized to have north and south poles 32a to 32d alternatively, four magnetic pole pieces 33a to 33d provided at the peripheral ends of said magnet 32 and a nonmagnetic material 31a such as aluminum or synthetic resin for embedding securely 15 said magnet and magnetic pole pieces. Said rotor 30 is connected to a crankshaft 34a of an engine.

With the magneto generator constructed as above described, for each revolution of the magneto generator, i.e., for each revolution of the engine crankshaft 34a, the capacitor charging coil 1 generates two cycles of the AC voltage as shown in FIG. 3(a), while the capacitor charging coil 2 generates two cycles of the AC voltages as shown in FIG. 3(b), which is retarded with respect to that of the coil 1 by an angle of about 60°. And for each revolution of the crankshaft 34a, the battery charging coil 3 generates two cycles of the AC voltages indicated by a solid line in FIG. 3(e) while the voltage of the coil 4 being indicated by a broken line in FIG. 3(e), wherein each voltage of said coils 3 and 4 are respectively retarded by an angle of about 120° with respect to each voltage of said coils 1 and 2.

The operation of the first embodiment constructed as described above will now be explained. The operation of the various parts of the embodiment which take place along with the rotation of the engine will be explained with reference to FIG. 3. When the generated voltage of the capacitor charging coil 1 begins to increase in the positive direction at a time T1 in FIG. 3, the capacitor 13 is charged with the voltage generated at the capacitor charging coil 1 flowing through a circuit comprising the coil 1, the diode 12, the capacitor 13 and a parallel circuit consisting of the diode 14 and the primary winding 15a of the ignition coil 15. Although at a time T2 a positive voltage is generated at the capacitor charging coil 2, the number of turns of the coil 2 is too small to charge the capacitor 13 at low speed rotation of the engine. Consequently, the capacitor 13 is finally charged to develop thereacross the terminal voltage as indicated by a solid line in FIG. 3(c). At a time T3 when the generated voltage of the coil 1 changes from the positive to the negative direction, the voltage generated at the coil 1 is shortcircuited through the circuit comprising the part 1b of the coil 1 and the diode 18 and the circuit comprising the other part 1a of the coil 1, the primary winding 20a of the transformer 20, the diode 19 and the part 1b of the coil 1. At this stage, an output voltage is produced at the secondary winding 20b as indicated by a solid line in FIG. 3(d) and the thyristor 17 is made conductive at a time T4 in FIG. 3, thereby to discharge the charge stored in the capacitor 13 through the circuit comprising the thyristor 17 and the primary winding 15a of the ignition coil 15 and to induce a high voltage at the secondary winding 15b of the ignition coil 15, thus sparking at the spark plugs 16. Here, the purpose of the diode 14 is to keep the current flowing through the primary winding

15a of the ignition coil 15 to extend the arc duration of the ignition spark. The above-mentioned operation is repeated twice for every rotation of the engine crank-shaft, namely two ignition sparks are caused for each revolution of the magneto generator. In the daytime, the switch means 27a and 27b are opened, and thereby the battery 25 is charged with the half wave voltage of the positive direction generated at the coils 3 and 4, whose waveforms are shown in FIG. 3(e) through the diodes 23 and 24, while in the nighttime, the switch means 27a and 27b are closed so that the lamp loads 28 are mainly supplied with the electric current from the full-wave rectifier 26.

Next the operation of the above-mentioned system will be explained when the engine is rotated in the reverse direction by accident. The generated voltages shown in FIG. 3 are changed in the opposite directions. During the very low speed operation of the engine, at a time T1' the capacitor 13 may be charged with the voltage generated at the coil 2 since the positive output voltage of the transformer 20 exists too short to make the thyristor 17 conductive, as indicated by a broken line in FIG. 3(d). And at a time T2' the charge stored in the capacitor 13 is discharged by the output signal of the transformer 20, thereby to cause ignition sparks at the spark plugs 16. However, during the low and high speed rotation of the engine, the duration of the positive output voltage of the transformer, as indicated by the one-dot-chain line in FIG. 3(d), becomes enough longer to make the thyristor 17 conductive, whereby the voltages produced at the coils 1 and 2 are bypassed through the thyristor 17 not to charge the capacitor 13. Therefore the engine is prevented from rotating in the reverse direction.

In the first embodiment as described above, the pole cores 7 and 11 on which the capacitor charging coil 2 and the battery charging coils 3 and 4 are respectively wound are positioned at the both adjacent sides of the pole core 6 on which the capacitor charging coil 1 is wound, as shown in FIG. 2. However, during the normal running of the engine, as the generated voltages of the coils 3 and 4 are cut by the diodes 23 and 24 when the thyristor 17 becomes conductive as shown in FIG. 3, the on-off operation of the switch means 27b has no influence on the generated voltage of the coil 1, whereby the fluctuation of the ignition timing due to the on-off operation of the switch means 27b is prevented.

Further in the first embodiment as described before, the generated voltage of the coil 2 may be fluctuated a little due to on-off operation of the switch means 27b, thereby causing fluctuation of the charging voltage of the capacitor 13 since the coils 2 and 3 are wound on the same pole core 7. To prevent the fluctuation of the charging voltage on the capacitor 13, only the capacitor charging coil 2 is to be wound on the pole core 7 without the battery charging coil 3 and the output voltage of the coil 4 is to be supplied to the battery 25 through the full-wave rectifier 26.

FIG. 4 shows the second embodiment of the present invention, in which the capacitor charging coil 1 is connected in series with the capacitor charging coil 2 whose generating voltage is retarded by the angle of 60° with respect to that of the coil 1 and the diodes 12 and 19 are respectively connected in parallel with the capacitor charging coils 2 and 1. The operation of the

second embodiment is almost the same as that of the first embodiment in FIG. 1.

FIG. 5 shows the third embodiment of the present invention. The ignition system of this embodiment comprises a high-speed capacitor charging coil 2a having a relatively low number of turns, a low-speed capacitor charging coil 2b having a relatively high number of turns, a thyristor 75 connected in parallel with the first coil 1, said thyristor 75 being controlled by the transformer 53 having a primary winding 53a connected in a series circuit of charging the capacitor 13 and a secondary winding 53b, the ignition coil 15 having the primary and secondary windings 15a and 15b, and the spark plug 16 connected to said ignition coil. In this FIG. 5 numerals 50, 74 and 76 designate diodes. Here, the phase difference between the first coil 1 and the capacitor charging coils 2a and 2b is designed to be about an angle of 60°.

The operation of the third embodiment will be explained with reference to FIG. 6 showing the waveforms produced at various points of the system. At a time T1 in FIG. 6, the voltage generated at the coils 2a and 2b as indicated by a solid line shown in FIG. 6(a) begins to increase in the positive direction, the capacitor 13 is charged through the circuit comprising the coil 2b, the coil 2a, the diode 22, the primary winding 53a of the transformer 53, the capacitor 13 and a parallel circuit of the primary winding 15a of the ignition coil 15 and the diode 14, as indicated by a broken line in FIG. 6(a). At this instance, the thyristor 75 is made conductive due to the output voltage of the transformer 53 indicated by a solid line shown in FIG. 6(d), whereby the voltage generated at the first coil 1 is short-circuited through the thyristor 75 as indicated by a broken line in FIG. 6(b). When the generated voltage of the capacitor charging coils 2a and 2b changes from the positive to the negative direction, the voltage is short-circuited through the circuit comprising the coils 2a and 2b, the ground, the primary winding 20a of the transformer 20 and the diode 19. And at this instance, an output voltage shown in FIG. 6(c) is generated at the secondary winding 20b of the transformer 20, and hence the thyristor 17 is made conductive at a time T2 in FIG. 6 and the charge stored in the capacitor 13 is discharged through the circuit comprising the diode 50, the thyristor 17, the ground, the primary winding 15a of the ignition coil 15 and the capacitor 13, thereby to induce a high voltage at the secondary winding 15b of the ignition coil 15 and thus finally causing the ignition spark at the spark plug 16. The abovementioned operation is repeated twice for each revolution of the engine crankshaft.

Next the operation of the third embodiment shown in FIG. 5 will be explained when the engine is rotated in the reverse direction by accident. The direction of the generated voltage of the coils is reversed during the reverse rotation of the engine. At a time T1' in FIG. 6 the generated voltage of the coils 2a and 2b is going to be stored in the capacitor 13, however, at this instance the thyristor 17 is already made conductive due to the output voltage of the coil 1 which is opposite to the solid line in FIG. 6(b). Therefore the series circuit of the coils 2a and 2b is short-circuited to the ground through the thyristor 17 thereby to prevent the spark plug 16 from causing the ignition spark.

FIG. 7 shows the fourth embodiment of the present invention, which operates in the same manner as the

third embodiment of FIG. 5. The fourth embodiment of FIG. 7 differs from the third embodiment in that the transformer 20 is replaced with a signal generator 87 having a capacitor 80, a thyristor 81, a zenor diode 82 and resistors 83, 85 and 89, and the charging current for the capacitor 13 is supplied to a gate of the thyristor 75. A numeral 88 is a diode and a resistor 86 indicated by a broken line in FIG. 7 may be employed for protecting the thyristor 75, which is connected between the gate and cathode of the thyristor 75.

FIG. 8 illustrates the fifth embodiment of the present invention in which the first coil 1 is employed as an electric source for both an ignition timing controlling means and a capacitor-charge-invalidating means, whose output voltage thereof is retarded by about 120° with respect to that of the capacitor charging coil 2.

The operation of the fifth embodiment will be explained with references in FIG. 9. Solid lines in FIG. 9 (a), (b) and (c) respectively show the generated voltages of the capacitor charging coil 2 and the first coil 1 and the output voltage of the signal generator 87 to be supplied to the gate of the thyristor 17 during the normal running of the engine. A broken line in FIG. 9(c) shows the output voltage of the signal generator 87 during the reverse rotation of the engine. At a time T1 in FIG. 9, when the generated voltage of the capacitor charging coil 2 increase in the positive direction, the capacitor charging current flows through the circuit comprising the coil 2, the diode 22, the capacitor 13, a parallel circuit of the diode 14 and the primary winding 15a of the ignition coil 15 and the ground, and thereby the capacitor 13 is charged as indicated by a broken line in FIG. 9(a). At a time T2 in FIG. 9, when the generated voltage of the first coil 1 increases in the negative direction, the current flows through the circuit comprising the first coil 1, the ground, the resistor 89, the capacitor 80, the resistor 83 and the diode 84 thereby to charge the capacitor 80. When, on the other hand, the voltage applied to the zenor diode 82 exceeds a predetermined value, the zenor diode 82 breaks down, thereby to make the thyristor 81 conductive, whereby the charge stored in the capacitor 80 discharges through the circuit comprising the capacitor 80, the gate of the thyristor 17, the cathode of the thyristor 17, the ground, the thyristor 81 and the resistor 83. At this instance, at the time T3 in FIG. 9 the thyristor 17 becomes conductive, whereby the charge stored in the capacitor 13 discharged through the circuit comprising the thyristor 17, the ground and the primary winding 15a of the ignition coil 15 to induce a high voltage at the secondary winding 15b, thus producing the ignition sparks at the spark plugs 16.

Here the ignition timing is so selected that the time duration of the gate signal for the thyristor 17 which is obtained by the discharge of the charge on the capacitor 80 may not overlap the time duration when the capacitor charging coil 2 begins to charge the capacitor 13.

Next the operation of the fifth embodiment will be explained with references in FIG. 9, when the engine is rotated in the reverse direction. The directions of the generated voltage of the coils 1 and 2 are reversed in FIG. 9. At a time T1' in FIG. 9, the capacitor 13 begins to be charged; however, in a little while the capacitor 80 is charged with the voltage generated at the coil 1 at a time T2' and then at a time T3' the thyristor 17 is made conductive due to the discharge current of the

charge on the capacitor 80. Consequently the capacitor charging coil 2 is short-circuited through the thyristor 17, thereby to prevent the capacitor from being charged, and the charge already stored in the capacitor 13 till the time T3' is discharged through the circuit comprising the thyristor 17, the ground and the primary winding 15a of the ignition coil 15 before the capacitor is charged sufficiently to cause the ignition spark at the spark plugs 16, whereby the reverse rotation of the engine is prevented.

FIG. 10 shows the sixth embodiment of the present invention, which aims to prevent the engine from rotating in the reverse direction. The main characteristic of the sixth embodiment is in that the thyristor 17 is supplied with a signal at its gate from a transformer 60 connected to the coil 1 before supplied with a signal from the transformer 20, thereby to short-circuit the capacitor charging coils 2a and 2b through the thyristor 17 during the reverse rotation of the engine. The generated voltage of the first coil 1 is retarded by 120° with respect to that of the coils 2a and 2b.

The operation of the sixth embodiment at the normal running of the engine will be explained with references in FIG. 9. The solid line in FIG. 9(a) shows the generated voltage of the coils 2a and 2b, the combined line of the broken line and the two-dot-chain line in FIG. 9(a) the charging voltage for the capacitor 13, the solid line in FIG. 9(b) the generated voltage of the first coil 1, the solid line in FIG. 9(d) the output voltage at the secondary winding 20b of the transformer 20 and the solid line in FIG. 9(e) the output voltage at the secondary winding 60b of the transformer 60. At the time T1 in FIG. 9, the capacitor 13 begins to be charged with the generated voltage of capacitor charging coils 2a and 2b irrespective of the signal from the transformer 60 at the gate of the thyristor 17 by a time T4 in FIG. 9, since before the time T4 the voltage appears between the anode and the cathode of the thyristor 17 is not sufficient to make it conductive thereby to maintain its off-state, as indicated by the broken line in FIG. 9(a). Then at a time T5 in FIG. 9, the thyristor becomes conductive due to the signal voltage from the transformer 20 and the charge stored in the capacitor 13 is discharged to induce a high voltage at the secondary winding 15b to produce the ignition sparks at spark plugs 16. The above-mentioned operation is repeated twice for each revolution of the engine.

Now the operation of the sixth embodiment at the reverse rotation of the engine will be explained. The generated voltage of the coils 2a 2b, and 1 will be respectively reversed with respect to the solid lines in FIG. 9(a) and (b). Broken lines in FIG. 9(d) and (e) show respectively the output voltages of the transformers 20 and 60. At the time T1' in FIG. 9, the capacitor 13 is going to be charged with the generated voltage of the capacitor charging coils 2a and 2b which is increasing in the positive direction, and at the time T2' the generated voltage of the coil 1 begins to increase in the negative direction to produce the output voltage at the transformer 60, and then at the time T3' the thyristor 17 becomes conductive to bypass the generated voltage of the coils 2a and 2b thereby to prevent the capacitor 13 from being charged any more and further to discharge the charge stored in the capacitor 13, however, at this instance, namely at the time T3', the charge on the capacitor is not sufficient to induce the high volt-

age, whereby the reverse rotation of the engine is prevented.

Now in the sixth embodiment as described above, the transformer 60 may be omitted from this embodiment 5 by connecting the coil 1 and the transformer 20 as indicated by a broken line in FIG. 10.

FIG. 11 illustrates the seventh embodiment of the present invention whose main characteristic is in that thyristor 17 is supplied at its gate with signals from the 10 transformer 53 connected in series in the capacitor charging circuit as well as the transformer 20 connected in parallel with the capacitor charging coils 2a and 2b and the thyristor 75 is connected at its anode to the secondary winding 53b of the transformer 53, 15 which is controlled by the generated voltage of the first coil 1. The phase difference between the first coil 1 and the capacitor charging coils 2a and 2b is designed to be about an angle of 60°.

FIG. 12 shows the waveforms produced at the various points of this system, in which, at the normal running of the vehicle, a solid line in FIG. 12(a) shows the generated voltage of the capacitor charging coils 2a and 2b, a solid line in FIG. 12(b) the generated voltage of the first coil 1, a solid line in FIG. 12(c) the output voltage at the secondary winding of the transformer 20 and a solid line in FIG. 12(d) the output voltage at the secondary winding 53b of the transformer 53. With references in FIG. 12, the operation of the seventh embodiment will be explained. At a time T1 in FIG. 12, the current flows through the circuit comprising the coil 1, the diode 74, the gate and the cathode of the thyristor 75 to make the thyristor 75 conductive and its conduction is maintained during the generated voltage of the coil 1 is in the positive direction, namely until a time T3 in FIG. 12. On the other hand, at a time T2 in FIG. 12 when the generated voltage of the capacitor charging coils 2a and 2b increases in the positive direction, the current flows through the circuit comprising the coils 2a and 2b, the primary winding 53a of the transformer 53, the diode 22, the capacitor 13, a parallel circuit of the diode 14 and the primary winding 15a of the ignition coil 15 and the ground, thereby to charge the capacitor 13 as indicated by a broken line 35 in FIG. 12(a). And at this instance, the output voltage of the transformer 53 is generated at the secondary winding 53b thereof, as shown in FIG. 12(d) by the solid line, which is short-circuited through the thyristor 75 since the thyristor 75 is in its conductive state as 40 mentioned above, whereby the thyristor 17 is not effective to be conductive by the voltage thus completing to charge the capacitor 13. And then at a time T4 in FIG. 12 when the generated voltage of the coils 2a and 2b changes from the positive to the negative direction, the 45 current flows through the circuit comprising the coils 2a and 2b, the ground, the primary winding 20a of the transformer 20 and the diode 19 and the other circuit of the coil 2b, the ground and the diode 18, whereby the output voltage as indicated by the solid line in FIG. 55 12(c) is generated at the secondary winding 20b of the transformer 20. At a time T5 in FIG. 12, the thyristor 17 is made conductive due to the output voltage of the transformer 20, thereby to discharge the charge stored in the capacitor 13 and to produce the ignition sparks 60 at the spark plugs 16. The operation as described above is repeated twice for each revolution of the engine in 65 this embodiment.

Next the operation in the reverse rotation of the engine will be explained with references in FIG. 12, in which a broken line in FIG. 12(c) shows the output voltage of the secondary winding 20b of the transformer 20 and a broken line in FIG. 12(d) the output voltage of the secondary winding 53b of the transformer 53. As mentioned before the directions of the generated voltage of the coils 1 and 2a and 2b are reversed. At a time T2' in FIG. 12, the capacitor 13 is going to be charged with the generated voltage of the coils 2a and 2b through the circuit including the primary winding 53a of the transformer 53, and at the same time, the output voltage as indicated by the broken line in FIG. 12(d) is generated at the secondary winding 53b of the transformer 53. At this stage, however, the thyristor 75 is in the off-state, thereby to supply the output voltage of the secondary winding 53b to the gate of the thyristor 17 to make it conductive. Therefore the generated voltage of the coils 2a and 2b is short-circuited through the thyristor 17 to prevent the capacitor 13 from being charged, whereby the reverse rotation of the engine is prevented.

FIG. 13 illustrates the eighth embodiment of the present invention, whose different characteristic from the seventh embodiment is in that the thyristor 17 is supplied at its gate with the timing signal which is generated at the transformer 20 connected in parallel with the first coil 1.

The operation of the eighth embodiment will be explained with references in FIG. 12. At first the solid lines in FIG. 12(a), (b), (d) and (e) are respectively showing the generated voltage of the coils 2a and 2b, the generated voltage of the coil 1, the output voltage at the secondary winding 53b of the transformer 53 and the output voltage at the secondary winding 20b of the transformer 20 in the case of the normal running of the engine. At the time T2 in FIG. 12, the capacitor 13 begins to be charged as indicated by the broken line in FIG. 12(a) without the current flowing through the thyristor 17 to the ground, and at this stage the output voltage generated at the secondary winding 53b of the transformer 53 is short-circuited through the thyristor 75 since the thyristor 75 is in the conductive state due to the generated voltage of the coil 1 at the gate of the thyristor 75. And then at the time T7 in FIG. 12, the thyristor 17 is made conductive due to the output voltage at the secondary winding 20b of the transformer 20 as shown by the solid line in FIG. 12(e), thereby to discharge the charge stored in the capacitor to produce the ignition sparks at the spark plugs 16. Secondary, in the case of the reverse rotation of the engine, the output voltages of the transformers 20 and 53 are shown by the broken lines in FIG. 12(d) and (e). Of course the directions of the generated voltages at the coils 1 and 2a and 2b are reversed. At the time T2' in FIG. 12, the capacitor 13 is going to be charged through the circuit including the transformer 53, and subsequently the output voltage as indicated by the broken line in FIG. 12(d) is generated at the secondary winding 53b. At this stage, the thyristor 75 is in the non-conductive state, and hence the thyristor 17 is made conductive by the generated voltage of the transformer 53 at its gate, whereby the capacitor 13 is prevented from being charged so that the reverse rotation of the engine is prevented.

Now the construction of the magneto generator G will be described, which may be employed in the sev-

enth and eighth embodiments shown in FIGS. 11 and 13. At first, in FIG. 14 a numeral 30' designates a rotor comprising an iron shell 31, four permanent magnets 32a', 32b', 32c' and 32d' spaced apart at equal intervals and securely embedded in the inner side of the iron shell 31 by means of a nonmagnetic material 31a' such as aluminum or resin, pole pieces 33a', 33b', 33c' and 33d' secured respectively to the inner face of the permanent magnets 32a', 32b', 32c' and 32d', and a center piece 34' securely mounted on the crankshaft 34a of the engine by a nut (not shown). The iron shell 31 is fixed to the center piece 34' by means of a rivet (not shown). A numeral 40 designates a stator secured to the engine, 6', 7' and 43 pole cores securely mounted on the stator 40 and spaced apart at equal intervals of 120°. These pole cores 6', 7' and 43 are wound with the coil 1, the capacitor charging coils 2a and 2b, the lamp-load coil 5 and so on.

Here, in FIG. 14, an additional pole core may be provided magnetically in parallel with the core 7' at the stator 40 or may be piled on the pole core 7' and the capacitor charging coils 2a and 2b may be wound respectively and separately on the pole core 7' and the additional pole core. And in like manner another pole core may be placed on the pole core 6' to wind the coil 1 and lamp-load coil 5 respectively. Even in these structure of the magneto generator, the generated voltages are also obtained as shown in FIG. 12(a) and (b).

When the magneto generator shown in FIG. 14 is employed in the ignition systems of the third and fourth embodiments shown in FIGS. 5 and 7, the lamp-load coil 5 is wound on the pole core 6', the coil 1 on the pole core 43 and the capacitor charging coils 2a and 2b respectively on the pole core 7' and the other pole core 35 which is placed magnetically in parallel with the pole core 7'.

And when the magnetic generator shown in FIG. 14 is employed in the system of the second embodiment shown in FIG. 4, the capacitor charging coil 2 is wound on the pole core 7' and the coil 1 on the pole core 6'.

And further when the magneto generator shown in FIG. 14 is employed in the system of the fifth embodiment shown in FIG. 8, the capacitor charging coil 2 is wound on the pole core 7' with the winding direction opposite to that of the coil 1.

And still further when the magneto generator shown in FIG. 14 is employed in the system of the sixth embodiment shown in FIG. 10, capacitor charging coils 2a and 2b are wound respectively on the pole core 7' and the other pole core which is provided magnetically in parallel with the pole core 7' in the magneto generator employed in the above-mentioned fifth embodiment.

Needless to say, here in FIG. 14, the disposal and number of pole cores may be changed in accordance with the characteristic and performance of the ignition system.

FIGS. 15-A and 15-B show another embodiment of the magneto generator which will be employed in the ignition systems of the seventh and eighth embodiments of the present invention shown in FIGS. 7 and 8. The rotor (not shown) of this magneto generator is just the same as that shown in FIG. 14. The pole core 43 wound with the lampload coil 5 is securely mounted on the stator 40 at a position displaced by about 180°, i.e., opposite to the pole core 6' wound with the coil 1. And the pole core 7' wound with the capacitor charging coils 2a and 2b is mounted on the pole core 6' wound

with the coil 1 and also the pole core 7' is moved by a certain angle with respect to the pole core 6' so that the generated voltage of the coils 2a and 2b may be advanced by about 60° in its phase to that of the coil 1.

In FIGS. 15-A and 15-B, the stator may be provided with an additional pole core magnetically in parallel with the pole core 7', wherein the capacitor charging coils 2a and 2b are wound respectively on the pole cores. In another arrangement of the magneto generator shown in FIGS. 15-A and 15-B, the pole core 6' wound with the coil 1 may be piled on or juxtaposed with the pole core 43 wound with the lampload coil 5. In a further arrangement of the magneto generator, the capacitor charging coils 2a and 2b may be wound on the pole core 6', the lamp-load coil 5 on the pole core 43 and the coil 1 on the pole core which is piled on or juxtaposed with core 43 so that the generated voltage of the coils 2a and 2b may be advanced by about 60° in its phase against that of the coil 1.

When the magneto generator shown in FIGS. 15-A and 15-B is employed in the ignition systems of the third and fourth embodiments shown in FIGS. 5 and 7, the coil 1 is wound on the pole core 7' and the capacitor charging coils 2a and 2b on the pole core 6' and another pole core provided in parallel with the pole core 6' or right or left thereof. And when the magneto generator in FIGS. 15-A and 15-B is employed in the second embodiment in FIG. 4, the capacitor charging coils 2a and 2b are replaced by the capacitor charging coil 2. And further when the magneto generator in FIGS. 15-A and 15-B is employed in the fifth embodiment in FIG. 8, the coils 2a and 2b are replaced by the coil 2 with the winding direction opposite to that of the coil 1. And still further when the magneto generator in FIGS. 15-A and 15-B is employed in the sixth embodiment in FIG. 10, the another pole core is juxtaposed with the pole core 7' with the capacitor charging coils 2a and 2b on said respective two pole cores.

FIGS. 16-A and 16-B show another arrangement of the stator of magneto generator, which will be employed in the third and fourth embodiments of the present invention shown in FIGS. 5 and 7. The rotor corresponding to the stator in FIGS. 16-A and 16-B is just the same as that in FIG. 14, and therefore the explanation is omitted. In this arrangement the pole cores 7a and 7b are piled together and securely mounted on the stator 40, on which the capacitor charging coils 2a and 2b are respectively wound. The other pole cores 6' and 43 are also mounted in the same manner as above on the stator and wound with the coil 1 and the lamp-load coil 5 therearound respectively. The pole cores 6' and 43 are so placed that the phase difference with respect to the cores 7a and 7b may be about 60°.

Similarly, the magneto generator shown in FIGS. 16-A and 16-B may be employed in the sixth embodiment in FIG. 10, in like manner.

Here in the fourth, fifth and sixth embodiments respectively shown in FIGS. 5, 7 and 10 in which the thyristor 17 is supplied at its gate with two kinds of signals from the different signal generators, the ignition performance may not be influenced by the change of the lamp loads since the pole core 6' for the coil 1 and the pole core 43 for the lamp-load coil 5 are magnetically isolated from the pole cores 7a and 7b for the coils 2a and 2b.

FIG. 17 shows the ninth embodiment of the present invention which differs from the first embodiment

shown in FIG. 1 in that the thyristor 17 is controlled by the signal voltage generated at timing signal coils 48a and 48b mounted on the timing signal generator TG provided in the magneto generator G and the thyristor 75 is controlled by the transformer 20 connected in parallel with the coil 1. In this embodiment, when the thyristor 75 is made conductive, the coils 1 and 2 are short-circuited respectively through the diodes 22a and 12 and the thyristor 75, however, the charge stored in the capacitor 13 is not discharged through the thyristor 75 because of the diode 22b. Accordingly, the capacitor 13 is charged with the voltages at the coils 1 and 2, and thereafter the capacitor 13 is discharged through the thyristor 17 which is made conductive by the signal from the timing signal generator TG.

The operation of the ninth embodiment shown in FIG. 17 will be explained with reference to FIG. 3. During the normal running of the engine, the generated voltage of the coil 1 is shown in FIG. 3(a), that of the coil 2 in FIG. 3(b), the charging voltage on the capacitor 13 is indicated by a broken line in FIG. 3(c), the output voltage of the transformer 20 indicated by the solid line in FIG. 3(d) and the output voltage of the timing signal generator TG is shown in FIG. 3(f). Therefore the normal running of the engine is carried on by the ignition spark at time T5 in FIG. 3. Then if the engine rotates in the reverse direction, the output voltage of the transformer 20 is indicated by a one-dot-chain line in FIG. 3(d), the coil 2 is short-circuited through the thyristor 75 at time T1' since at this instance the thyristor 75 is supplied with the signal voltage generated at the transformer 20 at its gate to become conductive, and subsequently the generated voltage of the coil 1 is short-circuited through the thyristor 75 at time T3'. These operation will be repeated during the reverse running of the engine, and therefore the capacitor 13 is not charged thereby to prevent the ignition sparks at the spark plug.

The construction of the magneto generator which will be employed in the ninth embodiment will be explained with reference to FIGS. 18-A and 18-B. The coils 1 and 2 are respectively wound on the pole cores 6' and 7' which are so placed that the phase difference therebetween may be about 60°. The pole core 43, on which the lamp-load coil 5 is wound is placed between the above-mentioned two pole cores 6' and 7'. A timing core 35 is provided in position on the center piece 34', which corresponds to the coils 48a and 48b of the timing signal generator TG. A numeral 22a designates a stator of the timing signal generator TG, which is mounted on the stator 40 at the position opposite to the pole core 43, and comprises a permanent magnet 46, pole cores 47a and 47b disposed on the opposite sides of the magnet 46, the generating coils 48a and 48b wound respectively on the pole cores 47a and 47b, a case 49 with a sealing resin 45 filled therein. A numeral 34b designates a nut for fixing the center piece 34' to the engine crankshaft 34a.

FIG. 19 shows the tenth embodiment of the present invention. The main characteristic of the tenth embodiment is in that the coil 1 is connected to the capacitor 13 through the primary winding 60a of the transformer 60 and the diode 12, the secondary winding 60b is connected to the gate of the thyristor 17 through the diode 74. The phase difference between the voltages of the coils 1 and 2 is designed to be about 90°.

The operation of the tenth embodiment will be explained with reference to FIG. 20. At a time T1, the generated voltage of the capacitor charging coil 2 increases in the positive direction, as indicated by solid line in FIG. 20(a) which is a no-load AC voltage thereof, and thereby the capacitor 13 is charged as indicated by a broken line in FIG. 20(a). AT a time T2, the generated voltage of the coil 1 is also going to charge the capacitor 13. The secondary winding 60b of the transformer 60 generates an output voltage as indicated by a solid line in FIG. 20(d) and the current flowing through the primary winding 60a is not sufficient to induce an output voltage at the secondary winding 60b to make the thyristor 17 conductive, since the capacitor 13 has been almost charged at the time T3. And then at a time T4 when the generated voltage of the coil 2 changes from the positive to the negative direction, the transformer 20 generates an output voltage at the secondary winding 20b thereof as indicated by a solid line in FIG. 20(c), and the thyristor becomes conductive to discharge the charge stored in the capacitor 13, thereby to produce the ignition sparks at the spark plugs 16. This operation will be repeated twice for each revolution of the magneto generator.

And if the engine rotates in the reverse direction, the generated voltage of the coil 1 is going to be stored in the capacitor 13 at time T1', however, the output voltage at the secondary winding 60b, as indicated by a broken line in FIG. 20(d), is sufficient to make the thyristor 17 conductive since the capacitor is not enough charged. Then, the coil 1 is short-circuited through the thyristor 17. And at time T2', the coil 2 is also short-circuited through the thyristor, and at a time T3' when the output voltage as indicated by a broken line in FIG. 20(c) appears at the secondary winding 20b and the thyristor 17 is made conductive, the ignition spark is not produced since the capacitor 13 is not charged at the time T3', whereby the reverse rotation of the engine is prevented.

In this tenth embodiment, the magneto generator shown in FIGS. 16-A and 16-B may be employed by omitting the pole core 7a wound with the coil 2a, winding the coil 2b on the pole core 7b and coils 1 and 5 are wound on the pole cores 6' and 43 which are so positioned that the phase difference between the voltages of the coils 1 and 2b may be about 90°.

FIG. 21 shows the eleventh embodiment of the present invention, which differs from the tenth embodiment shown in FIG. 19 in that the transformer 60 is omitted and a center tap 20c connected to the coil 1 is provided at the primary winding 20a and that one end of the primary winding 20a is connected to the ground through the diode 16 instead of the coil 1. And the operation of this eleventh embodiment is almost same as that of the tenth embodiment.

FIG. 22-A and 22-B show the structure of the magneto generator which can be employed in the ninth embodiment shown in FIG. 17.

The rotor 30 comprises an iron shell 31, eight permanent magnets 32a', 32b', 32c', 32d', 32e', 32f', 32g' and 32h' disposed at equal intervals and securely embedded in the inner side of the iron shell 31 by means of a nonmagnetic material 31a', another permanent magnet 32c', lain on the top of the magnet 32c' and magnetized radially but opposite to the magnet 32c', and pole pieces 33a', 33b', 33c', 33c', 33d', 33e',

33f', 33g' and 33h' secured respectively to the inner face of the permanent magnets 32a' to 32h'.

The stator 40 comprises a stator core 29' including six pole cores 6, 7, 8, 9, 10 and 47b' disposed at equal intervals and another pole core 47a' divided from the pole core 47b' and positioned at the place of the pole core 47b'. The coil 1 is wound on the pole core 6, the capacitor charging coil 2 on the pole core 7, coils 5a, 5b and 5c respectively on the pole cores 10, 9 and 8, and coils 48a and 48b of the timing signal generator respectively on the cores 47a' and 47b'. The coils 48a and 48b are connected so that when the divided pole cores 47a' and 47b' face the magnets other than the divided magnets 32c' and 32c', no electric current is generated, while when the divided pole cores 47a' and 47b' face the divided magnets 32c' and 32c', the ignition timing signal is generated at the timing signal generator, as shown in FIG. 23(a), once for each revolution of the engine crankshaft 34a.

Now the operation of the system in which the magneto generator shown in FIGS. 22-A and 22-B is employed in the ninth embodiment will be explained with reference to FIG. 23 showing the waveforms generated at each coil. The coil 1 generates a voltage as indicated by a solid line in FIG. 23(b) having an asymmetric four-cycle waveform for each rotation of the engine crankshaft, while the capacitor charging coil 2 generates a voltage shown in FIG. 23(c) having the same waveform as that of the coil 1 but retarded by about 60° with respect to that of the coil 1. Accordingly in the normal running of the engine, the capacitor 13 is charged, as indicated by a broken line in FIG. 23(b) with the generated voltages of the coils 1 and 2. Then the timing signal is generated at the timing signal generator, as shown in FIG. 23(a), to make the thyristor 17 conductive thereby to produce the ignition spark. A solid line in FIG. 23(d) shows the generated voltage at the secondary winding 20b of the transformer 20 during the normal running of the engine which makes the thyristor 75 conductive while the generated voltage of the coil 2 is in the positive direction, however, the charge stored in the capacitor 13 is prevented by the diode 22b from being discharged. On the contrary, during the reverse rotation of the engine the transformer 20 generates a voltage as indicated by a broken line in FIG. 23(d), and therefore as soon as the generated voltage of the coil 1 increases in the positive direction, the thyristor 75 is made conductive, whereby the generated voltage of the coil 1 passes through the thyristor 75 to the ground and successively the generated voltage of the coil 2 to the ground. Consequently the capacitor 13 is not charged to thus prevent the reverse rotation of the engine.

FIG. 24 shows the twelfth embodiment of the present invention whose main characteristic is in that the generated voltages in the negative direction of the coils 1 and 2 are detected by the timing signal generator 87 to make the thyristor 17 conductive.

The operation will be explained with reference to FIG. 20. The waveforms indicated by the solid lines in FIG. 20(a) and (b) showing respectively the generated voltages of the coils 2 and 1, whose phase difference is about 90°. During the normal running of the engine, the capacitor 13 is charged as indicated by a solid line in FIG. 20(g). Solid lines indicated in FIG. 20(e) and (f) show respectively the generated voltages at the timing signal generator 87 and when the generated voltage shown in FIG. 20(e) makes the thyristor 17 conductive

the capacitor 13 is discharged to induce the high voltage at the ignition coil 15, while when the generated voltage shown in FIG. 20(f) makes the thyristor 17 conductive the capacitor 13 has been already discharged thereby not to influence on the ignition spark performance. On the other hand, during the reverse rotation of the engine, broken lines indicated in FIG. 20(e) and (f) respectively show the generated voltages of the timing signal generator 87, thereby to produce the ignition spark at a time T_a as indicated by one-dot-chain line in FIG. 20(g).

FIG. 25 shows the ignition cycle of the ignition system now in question which is employed in a two-cylinder two-cycle engine. In this engine, the ignition sparks are produced at points A and A' respectively positioned at 20° of mechanical angle before a top and bottom deadcenters in the normal running of the engine. At the point A', the air-fuel mixture is not fired since the air-intake port and exhaust port are opened, and at the point A the air-fuel mixture is fired to rotate the engine. Now in the reverse rotation of the engine, when the ignition spark is produced at the time T_a , the piston is positioned at 35° of the mechanical angle after the top deadcenter, as indicated by B and B', neither the ignition spark at the point B can fire the air-fuel mixture since the air-intake port and the exhaust port are opened, nor the ignition spark at the point B' can produce the sufficient explosive energy for rotation the engine, whereby the reverse rotation of the engine is prevented.

In the above-mentioned embodiments employing the transformer or the timing signal generator for obtaining the ignition timing signal, the ignition timing is preferably advanced as the engine rotation increases. It is easy for the skilled person in this field to replace the timing signal generator to the transformer and the thyristor to the transisitor which are employed in above embodiments.

What we claim is:

1. A capacitor discharge type contactless ignition system for an internal combustion engine comprising;
a first capacitor charging coil mounted in a magneto generator driven by an engine and for generating a first alternating current in accordance with the rotation of said magneto generator; 45
a second capacitor charging coil mounted in said magneto generator and for generating a second alternating current in accordance with the rotation of said magneto generator whose phase is retarded by a certain angle from that of said first alternating current, whereby when the engine rotates in an undesired direction the second positive half wave of said second alternating current being generated prior to the first positive half wave or said first alternating current and the latter certain part of said second positive half wave overlapping the former certain part of said first positive half wave; 55
a capacitor means forming a capacitor charging circuit connected in series with said first and second capacitor charging coils and including rectifying means for rectifying said first and second alternating current and applying the rectified current to said capacitor; 60
means forming a capacitor discharging circuit including said capacitor, a semi-conductor switching element having a control gate and a primary winding

of an ignition coil having a primary and secondary winding;
a spark plug connected with said secondary winding of said ignition coil; and
a pulse generator connected with said control gate and for generating an ignition pulse in synchronism with the rotation of said magneto generator during the rotation of the engine in a desired direction, whereby the charge stored in said capacitor is discharged through said capacitor discharging circuit, to thereby induce a high voltage at said secondary winding to produce an ignition spark at said spark plug;
said pulse generator generating a reverse protecting pulse during the rotation of the engine in an undesired direction in order to make said semi-conductor switching element conductive for each period while said second positive half wave is generated, whereby said second positive half wave is short-circuited around said capacitor and said first positive half wave is sequentially short-circuited through said semi-conductor switching element due to the overlap of said first and second positive half wave, thus preventing said spark plug from producing an ignition spark which may otherwise keep the rotation of the engine in the undesired direction.

2. A capacitor discharge type contactless ignition system as defined in claim 1 wherein said pulse generator is a transformer whose primary winding is connected across said first capacitor charging coil and whose secondary winding is connected with said control gate whereby said ignition pulse and reverse protecting pulse are generated when the negative half wave is generated at said first capacitor charging coil.

3. A capacitor discharge type contactless ignition system as defined in claim 1 wherein said first and second capacitor charging coil are connected in series with each other.

4. A capacitor discharge type contactless ignition system as defined in claim 1 wherein said first and second capacitor charging coil are connected in parallel with said capacitor.

5. A capacitor discharge type contactless ignition system as defined in claim 1 wherein said pulse generator includes; a first transformer whose primary winding is connected across said first capacitor charging coil and whose secondary winding is connected with said control gate of said semi-conductor switching element whereby said ignition pulse is generated when the negative half wave is generated at said first capacitor charging coil; and

a second transformer whose primary winding is in series connected with said second capacitor charging coil and whose secondary winding is connected with said control gate of said semi-conductor switching element, whereby said reverse protecting pulse is generated at said secondary winding of said second transformer during the rotation of the engine in the undesired direction whenever the positive half wave is generated at said second capacitor charging coil.

6. A capacitor discharge type contactless ignition system as defined in claim 1 wherein said pulse generator includes a transformer having a primary and secondary winding,

the one part of said primary winding being in series connected with said second capacitor charging coil, the other part of said primary winding being connected across said second capacitor charging coil, and said secondary winding being connected with said control gate of said semi-conductor switching element whereby said ignition pulse is generated at said secondary winding during the ro- 5

tation of the engine in the desired direction whenever the negative half wave is generated at said second capacitor charging coil and said reverse protecting pulse is generated at said secondary winding during the rotation of the engine in the undesired direction whenever the positive half wave is generated at said second capacitor charging coil.
